UNITED STATES PATENT OFFICE

158,700

PARACHUTE TOY

Leo L. Weldon, Los Angeles, Calif.

Application December 15, 1947, Serial No. 143,140

Term of patent 3½ years

(Cl. D34—15)

To all whom it may concern:

Be it known that I, Leo L. Weldon, a citizen of the United States, residing at Los Angeles, in the county of Los Angeles and State of California, have invented a new, original, and ornamental Design for Parachute Toy, of which the following is a specification, reference being had to the accompanying drawing, forming a part thereof.

Figure 1 is a view in side elevation of a parachute toy, showing my new design, and with its parachute portion opened to its operative position.

Figure 2 is a perspective view of the parachute toy of Figure 1, but with its parachute portion folded and stowed within the toy's projectile portion in readiness to be projected into the air.

Figure 3 is a front elevation of the parachute toy as in Figure 2.

Figure 4 is a rear elevation of the parachute toy as in Figure 2.

I claim:

The ornamental design for a parachute toy, substantially as shown and described.

LEO L. WELDON.
